UNITED STATES PATENT OFFICE

127,338

DESIGN FOR A COSMETIC APPLICATOR

Charles E. Zimmerman, Chicago, Ill.

Application November 13, 1939, Serial No. 88,223

Term of patent 14 years

To all whom it may concern:

Be it known that I, Charles E. Zimmerman, a citizen of the United States, residing at Chicago, Cook county, Illinois, have invented a new, original, and ornamental Design for a Cosmetic Applicator, of which the following is a specification.

The design is shown in the accompanying drawing, which forms a part thereof, and in which:

The characteristic features of my design reside in the applicator disclosed having its peripheral edge concaved and fluted specifically as shown.

I claim:

The ornamental design for a cosmetic applicator, substantially as shown and described.

CHARLES E. ZIMMERMAN.
